MULTIPLE RECEPTACLE UNIT FOR SMALL PARTS

Paul V. Korth, Detroit, Mich.

Application August 31, 1953, Serial No. 26,647

Term of patent 14 years

(Cl. D58—26)

To all whom it may concern:

Be it known that I, Paul V. Korth, a citizen of the United States, residing at Detroit, in the county of Wayne and State of Michigan, have invented a new, original, and ornamental Design for a Multiple Receptacle Unit for Small Parts, of which the following is a specification, reference being had to the accompanying drawing, forming a part hereof.

Fig. 1 is a perspective view of a multiple receptacle unit for small parts showing my new design;

Fig. 2 is a cross sectional view taken on the line 2—2 of Fig. 1 with parts broken away for purpose of convenience; and

Fig. 3 is a cross sectional view taken on the line 3—3 of Fig. 2.

I claim:

The ornamental design for a multiple receptacle unit for small parts, as shown.
